UNITED STATES PATENT OFFICE.

DANIEL L. CHANDLER, OF BOSTON, MASSACHUSETTS, ASSIGNOR, BY MESNE ASSIGNMENTS, TO VEND ADS CORP., A CORPORATION OF MASSACHUSETTS.

COIN-OPERATED VENDING MACHINE.

Application filed January 19, 1923. Serial No. 613,754.

To all whom it may concern:

Be it known that I, DANIEL L. CHANDLER, a citizen of the United States, residing at Boston, in the county of Suffolk and State 5 of Massachusetts, have invented new and useful Improvements in Coin-Operated Vending Machines, of which the following is a specification.

This invention relates to a coin operated 10 vending machine.

The object of the invention is to provide a coin operated vending machine which, under certain conditions, will operate as follows:—

15 (1) When the correct coin is deposited in the machine and an article is in position ready for delivery, the machine will operate to deposit the coin in the machine, preferably in a suitable receptacle therefor, and 20 will deliver the article to the operator of the machine.

25 (2) When no coin is deposited in the machine and there is an article in position ready for delivery, the machine may be operated from the outside by the operator but no article will be delivered.

30 (3) When the correct coin, that is, a coin of predetermined dimensions is deposited in the machine, and there is no article positioned ready for delivery, then the coin will be returned to the operator.

35 (4) When a coin, or slug, of dimensions other than the exact dimensions of the coin which is intended to be deposited in the machine is placed in the machine and there is an article in the machine positioned ready for delivery, the coin or slug will be returned to the operator and the article will be retained in the machine.

40 (5) When a coin which is not of the correct dimensions or a slug, is deposited in the machine and there is no article positioned ready for delivery, then said coin will be returned to the operator.

45 It has been found when machines of this character are placed upon the market, that material other than coins, such as paper, paraffin, chewing gum, tooth picks, matches, etc., have been put into the coin slot and 50 forced down into the machine thus rendering the machine either inoperative, or else causing the machine to be so tampered with that the articles can be fed one by one out

of the machine without any coin being introduced into the machine. 55

It is one of the objects of this invention, in the event of any material other than the correct coin, whether it be a slug or a coin which is not intended to be used in the machine, for instance, a ten cent piece, where the machine is designed to be operated by a penny, to positively eject said material from the coin slot of the operating mechanism so that the mechanism shall not be rendered inoperative and so that the machine cannot be operated to deliver the articles without the proper recompense therefor. 60 65

The invention consists in the improved mechanism whereby the objects hereinbefore set forth are accomplished and particularly 70 in the combination of elements set forth in the claims, one of the novel features of the invention being embodied in a rotary coin holder which rotates in one direction to deposit the coin in the machine when the article is ready for delivery and when the coin is of a predetermined size, and which rotates in the opposite direction and ejects the coin from the machine in the event that the coin is not of a predetermined size, or in the event 75 that an article is not ready for delivery, and furthermore, the coin holder will be rotated and moved in said opposite direction to eject any foreign material therefrom and such foreign material will be positively ejected 80 from the coin holder. 85

Referring to the drawings:—

Figure 1 is a front elevation of a coin operated vending machine embodying my invention. 90

Fig. 2 is a sectional elevation of the machine taken on line 2—2, Fig. 1, with the magazine broken away.

Fig. 3 is a sectional elevation taken on line 3—3, Fig. 2, illustrating the rotary coin 95 holder.

Fig. 4 is a sectional elevation taken on line 4—4, Fig. 5.

Fig. 5 is an underneath plan of the machine. 100

Fig. 6 is an underneath plan partly in section of a portion of the machine taken on line 6—6, Fig. 2.

Fig. 7 is a detail sectional elevation taken on line 7—7, Fig. 6 and illustrating the movable stop and its operating mechanism. 105

Fig. 8 is a sectional elevation similar to Fig. 7 illustrating the parts in different positions.

Fig. 9 is a perspective view of the movable stop.

Fig. 10 is a perspective view of the coin detector finger.

Fig. 11 is a perspective view of the article detector finger.

10 Like numerals refer to like parts throughout the several views of the drawings.

In the drawings, 15 is the casing of the machine. 16 is the magazine for holding the articles to be vended. 17 is the coin drawer. 18 is a receptacle for the articles which are delivered outside the machine. 19 is the top of the machine upon which is mounted the magazine and on the under side of which is mounted all of the working mechanism of the machine.

There are embodied in the machine a primary slide 20 and a secondary slide 80. The primary slide carries with it the larger part of the working mechanism of the machine, and this primary slide is always operated to move toward and away from the front of the machine by a handle 22 fast to a shaft 23 rotatably mounted in bearings 24 which project downwardly from the underside of the top 19. A spring 25 rotates the shaft 23 in the opposite direction from that in which it is rotated by the handle 22. The shaft 23 is provided with a pawl and ratchet mechanism which insures the forward movement of the primary slide being continued to its end after it has once been started, and also insures the rearward movement of the slide being carried to its end when it has once been started. This pawl and ratchet mechanism consists, see Figs. 4 and 5, of a ratchet 26 fast to the shaft 23 and adapted to be engaged by a pawl 27 pivotally mounted on a stud 28 which is fast to a bracket 29 depending from the top 19 of the machine.

A spring 30 is connected at one end to the pawl 27 and at the other end to a pin 31 fast to the top of the machine. The ratchet 26 is provided with two oppositely disposed notches 32 and 33 and with a tooth segment 34, and when the operator starts the machine by pulling the handle 22 towards the front thereof the teeth of the segment 34 will rotate in the direction of the arrow *a* and be engaged by the swinging pawl 27 which will prevent the ratchet 26 from being moved in the opposite direction until the pawl enters the notch 32, then when the direction of rotation of the ratchet 26 is reversed, the pawl 27 will be tipped in the opposite direction and will engage the teeth of the segment 34 to prevent the ratchet from being rotated in the direction of the arrow *a* until the pawl again enters the notch 33.

The inner end of the shaft 23 has a crank arm 35 fast thereto which is provided with a crank pin 36 entering a vertical slot 37 in the front end of the primary slide 20, so that when the shaft 23 is rocked by the handle 22 and by the spring 25 alternately in opposite directions, the primary slide 20 will be moved forwardly or rearwardly sliding in ways 38 provided therefor in the top 19. 70

When in its normal position the rear end of the slide 20 abuts against a stop plate 39 fast to the underside of the top 19, as in Figs. 2, 5 and 6.

The present embodiment of my invention is illustrated as particularly adapted to contain and feed spherical articles such as balls of chewing gum, and the magazine 16 is provided with a base 40 which forms a part of the top 19 and in this base is a recessed portion 41 with inclined faces 42 operating to guide the balls of gum into a tubular receptacle 43 projecting downwardly from the underside of the primary slide 20 and forming a part thereof. Vertical pins 44 are fastened to the primary slide 20 and project upwardly into the magazine 16 and into the recessed portion 41 of the base of said magazine, so that as the primary slide 20 is moved forwardly and backwardly the pins 44 will agitate the articles in the magazine 15 and facilitate the feeding of the same into the receptacle 43.

The top 19 is provided with an orifice 45 preferably having inclined sides 46 which opens into a slot 47 provided in the primary slide 20, and in this slot is rotatably mounted a coin holder 48 which is fast to a rock shaft 49, Figs. 2, 3 and 5, rotatably mounted upon the slide 20. The shaft 49 has fastened at one end thereof a bevel gear 50 which meshes into another bevel gear 51 rotatably mounted upon a stud 51' fast to the primary slide 20. The rotary coin holder 48 has a recess 52 adapted to receive a coin 53 and another recess 54 provided to enable the coin holder 48 to clear the stationary ejector 63 when, after the coin holder has been partially rotated in the direction of the arrow *c*, Fig. 3, it is moved forwardly and the stationary ejector 65 enters the coin recess 52, and to enable the coin holder 48 to clear the ejector 65 when, after the coin holder has been partially rotated in the direction of the arrow *b*, Fig. 3, it is moved forwardly and the ejector 63 enters the coin recess 52. The rotary coin holder 48 is rocked in one direction or another, that is, referring to Fig. 3, it is rocked toward the left to deposit the coin 53 in the coin receptacle 17 when the coin is of the right size, that is of predetermined dimensions, and said coin member is rocked toward the right Fig. 3 to deposit a slug or anything which is not a coin of predetermined dimen- 125

sions, upon a chute 55 which is inclined downwardly and leads through an opening 56 into the receptacle 18. The gear 51 is rocked in one direction or the other for the 5 purposes hereinbefore set forth, by a bell crank lever 57 which is fastened thereto and has two arms 58 and 59. The arm 58 has an upwardly projecting lug 60 thereon and the arm 59 has an upwardly projecting lug 10 61 thereon.

When the slide 20 is moved forwardly and there is an article in the receptacle 43 ready to be delivered and there is also a coin 53 of predetermined size positioned in the recess 52 in the rotary coin holder 48, then the lug 60 will engage a stop 62 on the frame of the machine when the slide 20 arrives at its forward position and this will rotate the gear 51, thus rotating the gear 50 and its shaft 49 20 in the direction of the arrow *b*, Fig. 3, and the coin 53 will then be ejected from the notch 52 and dropped into the receptacle 17. The coin 53 is ejected from the recess 52 when the primary slide 20 is moved forwardly, by an ejector plate 63 which is fastened to a bracket 64 fast to the frame of the machine and which projects into the recess 52 and forces anything that may be therein out of said recess, for example, if the coin 25 53 has been placed in the recess and is held therein so that it would not fall out by gravity and enter the receptacle 17, it will be positively forced out by the stationary ejector 63. Any other material or article or 30 slug which may be in the notch 52 will be rotated by the coin holder 58 in the direction of the arrow *c*, Fig. 3, and forced out of the notch 52 by an ejector plate 65 which is also fastened to the bracket 64. A guide plate 66, 35 Fig. 3, which is fastened to and projects downwardly from the slide 20 serves to prevent any articles ejected from the coin holder 48, when the coin holder is rotated in the direction of the arrow *b*, from entering the chute 55 and also serves to prevent anything which is ejected from the recess 52, when the coin holder 48 rotates in the direction of the arrow *c*, from entering the coin receptacle 17.

It will be understood that the coin holder 48, therefore, is rotated in the direction of the arrow *b* when the article is being delivered to the operator and when the coin is of the right size, and it is rotated in the direction of the arrow *c* when any other combination of circumstances, as set forth in paragraphs (2), (3), (4) and (5), occurs, and this opposite rotation of the coin holder is obtained by the following instrumentalities:—As previously described, if the coin is correct and the article is ready for delivery, then the lug 60 engages the lug 62 and rocks the bell-crank lever 57 to rock the coin holder 48 in the direction of the arrow *b* and the coin is deposited in the receptacle 17,

and when the primary slide 20 returns to its normal position, the lug 60 will encounter another stop 67 on the frame of the machine and this will return the bell crank lever, the gears 50 and 51 and the coin holder to their 70 original and normal positions.

In causing the coin member to rotate toward the right, Fig. 3, under the circumstances and conditions set forth in paragraphs (2), (3), (4) and (5), or either of 75 them, a coin detector finger 68 is provided and an article detector finger 69 is provided, the coin detector finger 68 to operate when anything other than a coin of predetermined dimensions is deposited in the recess 52 and 80 the article detector finger to operate when no article is present. For delivery into the receptacle 18 there must be a combination of the two, that is, a correct sized coin and an article ready for delivery, in order to 85 secure the delivery of the article to the operator.

The detector finger 68 is pivoted at 70 to the primary slide 20 and the detector finger 69 is pivoted at 71 to an arm 72 fast to the primary slide 20, so that both of the detector fingers are pivoted to the primary slide 20 and always move forwardly and backwardly with it. The detector finger 68 is provided with an arm 73 which projects into a 95 slot 74 in the primary slide 20 and located in front of the coin slot 47. A spring 75 operates the detector finger 68 to move the end of the arm 73 against the coin 53 or other article that may be in the coin slot, that is, the spring 75 acts to move the arm 73 inwardly with relation to the coin slot. On its forward end the detector finger 68 is provided with an upwardly projecting lug 76 which engages the edge of a cam plate 77, 100 Fig. 5. When a coin of the proper dimensions is located in the coin recess then the lug 76, as the primary slide is moved forward, will clear the right hand end of an arm 78, Fig. 5, but if there is no coin in the 105 coin slot, then the detector finger 68 will be moved by the spring 75 so as to engage a tooth 79 provided at the right hand end of the arm 78, Fig. 5. The arm 78 is fastened to the secondary slide 80 which is guided to 110 slide in ways on the underside of the top of the machine and said slide 80 has an ear 81 thereon, see Fig. 7, which when the slide 80 is moved forwardly, or in the direction of the arrow *d*, Fig. 7, will engage an ear 82 projecting laterally from a movable stop 83 pivoted at 84 to the top 19 and as the slide 80 is moved forward by the slide 20 and coin 115 detector finger 68, the movable stop 83 will be rocked downwardly from the positions illustrated in Fig. 7 to that illustrated in Fig. 8 and thus will bring the ear 82 into the path of the lug 61 on the bell crank lever 57 and as the primary slide is moved forwardly the lug 61 will engage the movable 120 125 130

ear 82 before the lug 60 on the bell crank lever 57 can engage the stop 62.

Upon continued movement forward of the primary slide 20 the bell crank lever 57 will be rocked upon its pivot in the direction of the arrow *e*, Fig. 6, and this will cause the gear 51 to be rotated in the same direction, thus rotating the gear 50 in the direction of the arrow *c*, Fig. 3, and upon further forward movement of the slide 20 whatever foreign material may be located in the recess 52 of the coin holder 48 will be positively ejected by engaging the ejector plate 65. Thus it will be seen that if anything other than a correct coin is deposited in the recess 52 of the coin holder 48, the same will be ejected from the machine. If, however, a correct coin is deposited in the recess 52 and there is no article to be delivered to the operator, then the machine must operate to eject the coin from the machine and return it to the operator. To secure this result the secondary slide 80 is moved forwardly, as hereinbefore described, in order to bring the ear 82 into alignment with the lug 61 on the bell crank lever 57, when there is no article 14 in the receptacle 43, by the article detector finger which has an arm 85 which projects into the receptacle 43 through a slot 86 and is moved toward the article therein by a spring 87. The article detector finger 69 has a lug 88 projecting upwardly therefrom and bearing against the edge of a cam plate 89. If there is no article in the receptacle 43 then the arm 85 is carried into the receptacle and the detector finger 69 is swung in the direction of the arrow *f*, Fig. 5, to a sufficient distance so that an upwardly projecting ear 90 on said detector finger 69 will engage a downwardly projecting lug 91 on the secondary slide 80 as the primary slide 20 is moved forwardly. This will cause the slide 80 to be moved forwardly and will operate as hereinbefore described to cause the ear 81 on said slide 80 to engage the ear 82 and move it downwardly into the path of the lug 61 on the bell crank lever 57, with the result that the gears 51 and 50 will be operated to rotate the coin holder 48 in the direction of the arrow *c* and thus cause the coin 53 to be deposited in the chute 55 whence it will roll down into the receptacle 18, so that the operator can obtain his coin back because he has not obtained any article. A laterally projecting lug 96, Fig. 5, is secured on the under side of the secondary slide 80 at one end thereof, and when the primary slide 20 is returned to normal position by the spring 25, the secondary slide 80 is returned to normal position by a lug 72 secured on the under side of the primary slide, which engages the lug 96 and moves the secondary slide rearwardly. When the slide 80 moves backwardly together with

the primary slide 20 an ear 92 thereon will engage the stop 83 and move it back from the position illustrated in Fig. 8 to that illustrated in Fig. 7 where it will be out of the path of the lug 61 on the bell crank lever 57.

When there is an article 14 in the receptacle 43 and the slide 20 is moved forwardly, the arm 85 on the article detector finger 69 will be moved inwardly by the spring 87 until it engages said article and the detector finger will be allowed to be so moved by the lug 88 thereon moving into the recessed portion 93 of the cam plate 89, and the edge of this cam plate with which the lug 88 contacts is so formed as to allow the arm 85 of the detector finger 69 to engage the article 14, as the slide 20 is moved forwardly, until the receptacle tube 43 comes into alignment with and above a shelf 94, Fig. 2, whereupon the article detector finger is moved by the cam 89 out of engagement with the article and the article drops downwardly on to the shelf 94. Upon the return movement of the slide 20 the article is pushed off of the shelf 94, dropped on to the chute 55 and rolls downwardly into the receptacle 18. If, however, the auxiliary slide 80 is also moved forwardly by either of the detector fingers 68 or 69, as hereinbefore described, then a plate 95 on a downwardly projecting arm 96 fast to said secondary slide 80 will move forwardly with said slide and as it projects into and across the receptacle 43, the article 14 will not be allowed to drop down on to the shelf 94, but will return with the slides 20 and 80 to the position illustrated in Fig. 2 and in that case the article will not be delivered to the operator of the machine.

It will be understood that the stops 62 and 67 constitute stationary contacts; that the lugs 60, 61 and ear 82 are movable contacts, and that the lug 61 abuts against a stationary lug 82' constituting a stationary contact when the slide 20 is returning to its normal position as illustrated in Fig. 6, whereby the bell crank lever 57 is rotated to assume its normal position and thereby the gears 50 and 51 and the coin holder 48 are rotated to assume their normal positions. The secondary slide 80 is held by frictional resistance in any position to which it may be moved, by a spring 97 fast to the top 19 and having an arm 98 thereon which bears against the underside of the secondary slide 80.

The general operation of the mechanism hereinbefore specifically and to some extent in general described is as follows:—The user of the machine places a coin of the proper dimensions, that is, a penny for a penny machine, a nickel for nickel machine, or a dime for a dime machine, in the orifice 45 whence it descends through the slot 47

in the slide 20 into the recess 52 in the coin holder 48.

Assuming now that an article 14 is in the receptacle 43 in the position illustrated in

- 5 Fig. 2 and the coin in the position illustrated in Fig. 3, the operator of the machine pulls the handle 22 forwardly thus rotating the shaft 23 through the pawl and ratchet mechanism, and the slide 20 is brought forward while the slide 80 remains stationary until the coin holder is rotated in the direction of the arrow *b* by the lug 60 abutting against the stop 62 and the coin is pushed out of the recess 52 by the ejector plate 63.
- 10 At the same time that this is occurring the slide 20 moves the receptacle 43 forwardly carrying the article 14 off of the plate 95 and dropping it on to the plate 94, then upon releasing the handle 22 the spring 25
- 15 will return the slide 20 to its normal position, together with the slide 80 and during this backward movement the receptacle will push the article off of the shelf 94, whereupon it will be dropped into the chute 55 and
- 20 roll down on to the receptacle 18. This is the sequence of operations performed by the machine when a coin of predetermined dimensions is deposited therein and when the package is ready for delivery.

- 25 Assuming that the combination of circumstances set forth in paragraph (2) occurs, where there is no coin deposited in the machine, but there is an article 14 ready for delivery, in this case, when the machine is operated by the handle 22, the coin detector finger 68 will be moved into the coin slot and the lug 76 will engage the tooth 79 on the arm 78 and the slide 80 will be carried forwardly along with the slide 20. The ear 83 on the movable stop 82 will be drawn downwardly into the path of the lug 61 on the bell crank lever and this will rotate the bell crank lever so as to move the gears to rock the coin holder in the direction of the arrow *c*, and at the same time the plate 95 will be carried along with the receptacle 43 and back again with it, so that there will be no article delivered from the machine.

- 30 When the combination of circumstances is as set forth in paragraph (3) wherein a correct coin is deposited but there is no package, then the coin detector finger is held out, but the article detector finger 69 moves in the direction of the arrow *f*, Fig. 5, so that the ear 90 thereon engages the lug 91 on the slide 80 and said slide is then moved with the slide 20, and by the mechanism hereinbefore described the coin holder 48 is rotated in the direction of the arrow *c* and the coin is delivered to the operator of the machine.

- 35 If the combination of circumstances set forth in paragraph (4) occurs then the coin detector finger 68 is moved sufficiently to allow the lug 76 to engage the tooth 79 and

move the slide 80, with the result that the coin holder 48 is rotated in the direction of the arrow *c* and returns the slug to the operator of the machine but also retains the package.

40 When the combination of circumstances set forth in paragraph (5) occur and there is a slug which is thinner than the penny positioned in the recess 52, then the coin detector finger 68 will be moved so that the lug 76 will engage the tooth 79 and moving the slide 20 will actuate the instrumentalities hereinbefore described, to rotate the coin holder 48 in the direction of the arrow *c*, returning the slug to the operator of the machine. If the slug is exactly of the same dimensions as the penny, then the coin holder will rotate in the direction of the arrow *b* and the slug will be deposited in the coin receptacle in the casing. The slot 47 is of such dimensions that a coin or slug which is of greater thickness than a penny could not be introduced into it.

I claim:

1. A machine for vending articles having, in combination, a movable member adapted to receive a coin and mechanism rendered operable by one of said articles and said coin to operate said movable member to deposit said coin within said machine when the coin is of predetermined dimensions and to eject the coin from the machine when not of predetermined dimensions.

2. A machine for vending articles having, in combination, a rotary member adapted to receive a coin and mechanism rendered operable by one of said articles and by said coin to rotate said member and to deposit said coin within said machine when the coin is of predetermined dimensions and to eject the coin from the machine when not of predetermined dimensions.

3. A machine for vending articles having, in combination, a rotary member adapted to receive a coin and mechanism rendered operable by one of said articles and by said coin to rotate said member in one direction and deposit said coin within said machine when the coin is of predetermined dimensions and to rotate said member in the opposite direction and eject the coin from the machine when not of predetermined dimensions.

4. A machine for vending articles having, in combination, a rotary member provided with a recess in its periphery adapted to receive a coin and mechanism rendered operable by one of said articles and by said coin to rotate said member and deposit said coin within said machine when the coin is of predetermined dimensions and to eject the coin from the machine when not of predetermined dimensions.

5. A machine for vending articles having, in combination, a movable member provided

- with a slot adapted to receive a coin, a detector finger pivoted to said movable member, yielding means adapted to move one end of said detector finger into said slot, a rotary member mounted on said movable member, projecting into said slot and adapted to receive said coin, and mechanism on said movable member rendered operative by said detector finger to rotate said rotary member in one direction to deposit a coin within said machine and to rotate said rotary member in the opposite direction to eject a coin from said machine.
6. A vending machine having, in combination, a reciprocatory member constituting a receptacle for an article and provided with a slot adapted to receive a coin, a rotary member mounted on said reciprocatory member and projecting into said slot, said rotary member being provided with a recess adapted to receive said coin, a detector finger mounted on said reciprocatory member adapted to engage a coin in said slot, mechanism rendered operable by said coin detector finger to impart a rotary motion to said coin holder in one direction and stationary means adapted to operate said rotary member to rotate in the opposite direction.
7. A machine for vending articles having, in combination, a rotary and reciprocating coin holder and mechanism to rotate said holder and eject a coin therefrom.
8. A machine for vending articles having, in combination, a rotary and reciprocating coin holder and mechanism to rotate said holder and eject a coin therefrom and means to guide said coin out of said machine.
9. A machine for delivering an article in return for a coin of predetermined dimensions deposited therein having, in combination, a rotary coin holder and mechanism rendered operable by a coin of dimensions other than those of said coin of predetermined dimensions and positioned in said holder to rotate said holder and eject the coin therefrom.
10. A machine for delivering an article in return for a coin of predetermined dimensions deposited therein having, in combination, a rotary coin holder, mechanism rendered operable by a coin of dimensions other than those of said coin of predetermined dimensions and positioned in said holder to rotate said holder and eject the coin therefrom and means to guide said coin out of said machine.
11. A machine for delivering an article in return for a coin of predetermined dimensions deposited therein having, in combination, a rotary and reciprocating coin holder provided with a recess for said coin and mechanism adapted to rotate said holder and positively eject from said recess anything that may be contained therein.

12. A machine for delivering an article in return for a coin of predetermined dimensions deposited therein having, in combination, a rotary coin holder provided with a recess for said coin and mechanism adapted to rotate said holder in one direction and eject therefrom a coin of predetermined dimensions and to rotate said holder in the opposite direction and eject from said recess any material other than a coin of predetermined dimensions that may be contained therein.

13. A machine for delivering an article in return for a coin of predetermined dimensions deposited therein having, in combination, a rotary coin holder provided with a recess for said coin, mechanism adapted to rotate said holder in one direction and eject therefrom a coin of predetermined dimensions and to rotate said holder in the opposite direction and eject from said recess any material other than a coin of predetermined dimensions that may be contained therein and means to guide said material out of said machine.

14. A machine for delivering an article in return for a coin of predetermined dimensions deposited therein having, in combination, a casing provided with a coin slot, a coin holder in said casing provided with a recess to receive said coin, a movable member upon which said coin holder is rotatably mounted, mechanism to rotate said holder positioned on said movable member and means rendered operable by a coin in said recess of predetermined dimensions and by said article to rotate said holder and eject the coin therefrom.

15. A machine for delivering an article in return for a coin of predetermined dimensions deposited therein having, in combination, a casing provided with a coin slot, a coin holder in said casing provided with a recess to receive said coin, a movable member upon which said coin holder is rotatably mounted, mechanism to rotate said holder positioned on said movable member and means rendered operable by a coin in said recess of predetermined dimensions and by said article to rotate said holder in one direction and eject the coin from said recess and into said casing and to rotate said holder in the opposite direction and eject from the casing anything that may be contained in said recess when said coin of predetermined dimension is not positioned in said recess.

16. A machine for delivering an article in return for a coin of predetermined dimensions deposited therein having, in combination, a casing provided with a coin slot, a coin holder in said casing provided with a recess to receive said coin, a movable member upon which said coin holder is rotatably mounted, mechanism to rotate said holder

positioned on said movable member and means rendered operable by a coin in said recess of predetermined dimensions and by said article to rotate said holder in one direction and eject the coin from said recess and into said casing and to rotate said holder in the opposite direction and eject from the casing anything that may be contained in said recess when said article is not 10 positioned on said movable member.

17. A machine for delivering an article in return for a coin of predetermined dimensions deposited therein having, in combination, a casing provided with a coin slot, a coin holder in said casing provided with a recess to receive said coin, a primary slide upon which said coin holder is rotatably mounted, mechanism positioned on said slide to rotate said holder and embodying a movable contact member, and a stationary contact member on said casing adapted to be engaged by said movable contact member when said primary slide is moved forwardly with a coin of predetermined dimensions in said recess and carrying said article to deposit said coin in said casing and deliver said article from said casing.

18. A machine for delivering an article in return for a coin of predetermined dimensions deposited therein having, in combination, a casing provided with a coin slot, a coin holder in said casing provided with a recess to receive said coin a primary slide upon which said coin holder is rotatably mounted, mechanism positioned on said slide to rotate said holder and embodying a movable contact member, and a stationary contact member in said casing adapted to be engaged by said movable contact member and rotate said coin holder in one direction when said primary slide is moved forwardly with a coin of predetermined dimensions in said recess and carrying said article to deposit said coin in said casing and deliver said article from said casing and another stationary contact member on said casing adapted to be engaged by said movable contact member on the return movement of said primary slide to rotate said coin holder in the opposite direction to its normal position.

19. A machine for delivering an article in return for a coin of predetermined dimensions deposited therein having, in combination, a casing provided with a coin slot, a coin holder in said casing provided with a recess to receive said coin, a primary slide slidable on said casing and constituting a holder for an article, a secondary slide on said casing and means on said secondary slide to prevent an article being delivered from said primary slide when said slides are connected to move together and means governed by said article to connect said slides together.

20. A machine for delivering an article in

return for a coin of predetermined dimensions deposited therein having, in combination, a casing provided with a coin slot, a coin holder in said casing provided with a recess to receive said coin, a primary slide 70 upon which said coin holder is rotatably mounted, mechanism positioned on said slide to rotate said holder, a movable contact member on said slide, a movable contact member on said casing, means to position 75 said movable contact member on said casing to be engaged by the movable contact member on said primary slide, to rotate said coin holder and deliver said coin from said casing when there is no article delivered 80 from said casing by the forward movement of the slide.

21. A machine for delivering an article in return for a coin of predetermined dimensions deposited therein having, in combination, a primary slide constituting an article receptacle and a secondary slide in said casing, a coin holder rotatably mounted on said primary slide and provided with a recess adapted to receive a coin, a detector 90 finger on said primary slide adapted to engage a coin or other material in said recess, another detector finger on said primary slide adapted to engage an article on said slide, either of said fingers being adapted to engage said secondary slide and move it with said primary slide and mechanism rendered operable by the movement of said secondary slide with said primary slide, to rotate said coin holder and to eject said coin or material 100 from said casing.

22. A machine for delivering an article in return for a coin of predetermined dimensions deposited therein having, in combination, a primary slide constituting an article 105 receptacle and a secondary slide in said casing, a coin holder rotatably mounted on said primary slide and provided with a recess adapted to receive a coin, a detector finger on said primary slide adapted to engage a coin or other material in said recess, another detector finger on said primary slide adapted to engage an article on said slide, either of said fingers being adapted to engage said secondary slide and move it with said primary slide and means rendered operable by the movement of said secondary slide with said primary slide to prevent said article from being ejected from said primary slide.

23. A machine for delivering an article in return for a coin of predetermined dimensions deposited therein having, in combination, a primary slide constituting an article receptacle and a secondary slide in said casing, a coin holder rotatably mounted on said primary slide and provided with a recess adapted to receive a coin, a detector finger on said primary slide adapted to engage a coin or other material in said recess, another detector finger on said primary slide 120 125 130

adapted to engage an article on said slide, either of said fingers being adapted to engage said secondary slide and move it with said primary slide, mechanism rendered operable by the movement of said secondary slide with said primary slide, to rotate said coin holder and to eject said coin or material from said casing and means rendered operable by the movement of said secondary slide with said primary slide to prevent said article from being ejected from said slide.

24. A machine for delivering an article in return for a coin of predetermined dimensions deposited therein having, in combination, a primary slide constituting an article receptacle and a secondary slide in said casing, a coin holder rotatably mounted on said primary slide and provided with a recess adapted to receive a coin, a detector finger on said primary slide adapted to engage a coin or other material in said recess, another detector finger on said primary slide adapted to engage an article on said slide, either of said fingers being adapted to engage said secondary slide and move it with said primary slide and mechanism rendered operable by the movement of said secondary slide with said primary slide, to rotate said coin holder and to eject said coin or material from said casing, said coin detector finger being rendered inoperative by a coin of predetermined dimensions positioned in said recess to connect said secondary to said primary slide.

25. A machine for delivering an article in return for a coin of predetermined dimensions deposited therein having, in combination, a primary slide constituting an article receptacle and a secondary slide in said casing, a coin holder rotatably mounted on said primary slide and provided with a recess adapted to receive a coin, a detector finger on said primary slide adapted to engage a coin or other material in said recess, another detector finger on said primary slide adapted to engage an article on said slide, either of said fingers being adapted to engage said secondary slide and move it with said primary slide and means rendered operable by the movement of said secondary slide with said primary slide to prevent said article from being ejected from said slide, said article detector finger being rendered inoperative by an article on said primary slide to connect said secondary to said primary slide.

26. A machine for delivering an article

in return for a coin of predetermined dimensions deposited therein having, in combination, a primary slide constituting an article receptacle and a secondary slide in said casing, a coin holder rotatably mounted on said primary slide and provided with a recess adapted to receive a coin, a detector finger on said primary slide adapted to engage a coin or other material in said recess, another detector finger on said primary slide adapted to engage an article on said slide, either of said fingers being adapted to engage said secondary slide and move it with said primary slide and mechanism mounted on said primary slide including a movable contact member to rotate said coin member, and a movable contact member on said casing operable by said secondary slide to be positioned to engage the movable contact member on said primary slide and rotate said coin holder to eject said coin or material from said recess.

27. A machine for delivering an article in return for a coin of predetermined dimensions deposited therein having, in combination, a primary slide constituting an article receptacle and a secondary slide in said casing, a coin holder rotatably mounted on said primary slide and provided with a recess adapted to receive a coin, a detector finger on said primary slide adapted to engage a coin or other material in said recess, another detector finger on said primary slide adapted to engage an article on said slide, either of said fingers being adapted to engage said secondary slide and move it with said primary slide, mechanism mounted on said primary slide including a movable contact member to rotate said coin member, and a movable contact member on said casing operable by said secondary slide to be positioned to engage the movable contact member on said primary slide and rotate said coin holder to eject said coin or material from said recess and a stationary contact member on said casing positioned to engage the movable contact member on said primary slide during its return movement to return the same to its normal position.

In testimony whereof I have hereunto set my hand in presence of two subscribing witnesses.

DANIEL L. CHANDLER.
